UNITED STATES PATENT OFFICE.

JEAN PIERRE GELAS, OF ST. ETIENNE, FRANCE.

DESIGN FOR A PATTERN FOR TEXTILE FABRICS.

SPECIFICATION forming part of Design No. 22,180, dated January 31, 1893.

Application filed November 28, 1892. Serial No. 453,424. Term of patent 3½ years.

To all whom it may concern:

Be it known that I, JEAN PIERRE GELAS, of St. Etienne, Department of Loire, France, have invented and produced a new and original Design for a Pattern for Textile Fabrics, of which the following is a specification, reference being had to the accompanying drawing, forming a part thereof.

The pattern shown is intended for button stock.

The figure is a plan view of a strip of button stock showing my design.

The leading feature of my design is the button-like figure produced upon the strip of button stock and comprising intersecting right angled band-like figures, the middle portions of which are given a twisted columnar appear-

ance. The button stock 10 is produced in a strip, while at intervals thereon are the button-like figures 11, consisting of intersecting right angled band-like figures 12, 12^a, the middle portions of which are given a twisted columnar appearance. The rectangular figures formed by the right angled band-like figures 12 are given a wavy appearance by parallel weaving lines, and this wavy surface forms the background of the button-like figure.

I claim—

The design for button stock herein shown and described.

JEAN PIERRE GELAS.
